Eric Burtis, Los Angeles, Calif.

Application March 19, 1945, Serial No. 118,587

Term of patent 14 years

(Cl. D85—2)

To all whom it may concern:

Be it known that I, Eric Burtis, a citizen of the United States, residing at Los Angeles, in the county of Los Angeles and State of California, have invented a new, original, and ornamental Design for a Tobacco Bowl or Similar Article, of which the following is a specification, reference being had to the accompanying drawing, forming part thereof.

Figure 1 is a perspective view of a tobacco bowl or similar article showing my new design.

I claim:

The ornamental design for a tobacco bowl or similar article, substantially as shown.

ERIC BURTIS.
